(57) CLAIM

The ornamental design for a comb as shown and described.

DESCRIPTION

FIG. 1 is a front perspective view of a comb showing a first embodiment of the claimed design.

FIG. 2 is a front view of the comb of FIG. 1, wherein the rear view is a mirror image thereof.

FIG. 3 is a left side view of the comb of FIG. 1.

FIG. 4 is a right side view of the comb of FIG. 1.

FIG. 5 is a top view of the comb of FIG. 1.

FIG. 6 is a bottom view of the comb of FIG. 1.

FIG. 7 is a front perspective view of a comb showing a second embodiment of the claimed design.

FIG. 8 is a front view of the comb of FIG. 7, wherein the rear view is a mirror image thereof.

FIG. 9 is a left side view of the comb of FIG. 7.

FIG. 10 is a right side view of the comb of FIG. 7.

FIG. 11 is a top view of the comb of FIG. 7; and,

FIG. 12 is a bottom view of the comb of FIG. 7.

The broken lines illustrating portions of the comb form no part of the claimed design.

1 Claim, 8 Drawing Sheets
